WILLIAM GILMORE, OF HUDSON CITY, NEW JERSEY.

Letters Patent No. 84,350, dated November 24, 1868.

IMPROVEMENT IN TENONING-MACHINES.

The Schedule referred to in these Letters Patent and making part of the same.

To all whom it may concern:

Be it known that I, WILLIAM GILMORE, of Hudson City, in the county of Hudson, and State of New Jersey, have invented a new and useful Improvement in Tenoning-Machine; and I do hereby declare that the following is a full, clear, and exact description thereof, which will enable those skilled in the art to make and use the same, reference being had to the accompanying drawings, forming part of this specification.

This invention relates to improvements in machines for forming tenons on wood-framing, and consists in the arrangement of a sliding clamping-carriage on a table, and a pair of vertically-reciprocating cutters on a suitable frame, and operated by foot-power, as will be more fully described on reference to the accompanying drawings, in which—

Figure 1 represents a side view of my improved machine;

Figure 2, a front end of the same; and

Figure 3, a section of the sliding carriage and clamp, in the line $x x$ of fig. 1.

Similar letters of reference indicate corresponding parts.

A represents the framing of the machine.

B, the table, on which the vertical carriage C slides in ways arranged in a vertical position.

D is a vertically-reciprocating yoke, which carries the cutters E E, which are connected to the said yoke adjustably.

F is a treadle, by which the cutter-gate or yoke is moved downward against the action of the springs. The springs raise the cutter-gate, and keep it in an elevated position, when the pressure of the foot is taken off the treadle F.

a is a vertical rod, arranged to slide loosely in the brackets $a' a'$. The lower end bears on the top of the cutter-gate, by which, and by the action of gravitation, it receives a reciprocating motion, which it communicates to the pawl-lever d through the medium of the wiper b.

The pawl-arm d carries a pawl, d^1 , working into the

rack on the top of the carriage, and feeds it towards the cutters.

d is a holding-pawl, which prevents the work from being driven away from the cutters by their action on it.

e is a clamp, having a clamping-screw, e', by which the material, on which the tenon is to be formed, is clamped to the carriage, to be fed along to the cutters. The said clamp is secured to the carriage in a slot, whereby it may be raised or lowered on the same, to hold material of various sizes.

To operate my improved machine, a piece of timber is placed on the table and screwed up against the carriage by the clamping-screw, the carriage being drawn back far enough for the said piece of timber to be fed up to the cutters the desired amount.

If the material be so thin as to be too far towards the carriage to admit of the tenon being formed at the right distance from the face of the work, blocks of wood may be interposed between it and the face of the carriage.

It is then clamped tightly by the screw.

The knives are then adjusted to the proper position on the gate, and also to the proper distance apart, and the machine set in motion by the application of the foot to the treadle F, by which the said timber is fed up to the cutters, and the tenon formed on both sides at the same time, as will be fully understood without further description.

Having thus fully described my invention,

What I claim, and desire to secure by Letters Patent, is—

The combination of the pawl-arm d, vertically-sliding rod a, and pawls d^1 d^2 , with the vertical carriage C, all arranged and operating as described, for the purpose specified.

The above specification of my invention signed by me, this 18th day of February, 1868.

Witnesses: WILLIAM GILMORE.

W.M. F. McNAMARA,

ALEX. F. ROBERTS.
